UNITED STATES PATENT OFFICE.

JOHN ROBERT McFARLIN, OF PHILADELPHIA, PENNSYLVANIA, ASSIGNOR TO ELECTRIC SERVICE SUPPLIES COMPANY, OF PHILADELPHIA, PENNSYLVANIA, A CORPORATION OF PENNSYLVANIA.

LIGHTNING-ARRESTER.

1,277,095.

Specification of Letters Patent. Patented Aug. 27, 1918.

Application filed October 26, 1916. Serial No. 127,798.

To all whom it may concern:

Be it known that I, JOHN R. McFARLIN, a citizen of the United States, residing in the city of Philadelphia, county of Philadelphia, and State of Pennsylvania, have invented certain Improvements in Lightning Arresters, of which the following is a specification.

My invention relates to lightning arresters of the expulsion type and my leading object is to protect electric apparatus from lightning and other high voltage by improved means of simple and efficient character adapted for discharging to ground excessive current in line wires and for preventing the flow of normal current from such wires to ground.

In my invention, in its preferred form, I employ an insulating case or housing containing in series non-inductive resistance and a plurality of air gaps adapted for efficiently heating the adjacent air and causing a blast that will eliminate the arc and destroy the conducting path of ionized air of a gap between concentrically disposed electrodes at the outlet from the housing, the air expanded by the heat being drawn to a restricted annular passage forming an expulsion gap between the electrodes and exerting the desired force of such character as to effectively interrupt the flow of current to ground.

A desideratum attained by my invention is a high degree of efficiency combined with flexibility which admits of the ready adjustment of the apparatus so that it will operate efficiently under varying conditions.

In this arrester the air gap distance is so adjusted that normal line potential will not break it down and arc over, but a rise of potential slightly higher than the normal will, hence maximum protection to the apparatus is afforded.

The characteristic features of my improvements will more fully appear from the following description and the accompanying drawings in illustration thereof.

In the drawings, Figure 1 is a side elevation of apparatus embodying my invention; Fig. 2 is a broken top plan view of the same; Fig. 3 is a broken bottom plan view; Fig. 4 is a sectional view on the line 4—4 of Fig. 2; Fig. 5 is a sectional view on the line 5—5 of Fig. 4; Fig. 6 is a sectional view on the line 6—6 of Fig. 4; Fig. 7 is a sec-

tional view on the line 7—7 of Fig. 4; and Fig. 8 is a sectional view on the line 8—8 of Fig. 4.

My invention, in the form thereof illustrated in the drawings, comprises a tubular case or housing body 1, provided with the supporting lugs 1^a, the cap 1^b, and the bottom 1^c; the parts of the case being formed of suitable insulating material such as porcelain.

A conducting cap or cap plate 2, provided with the dished center 2' with clips 2'' cut therefrom, has its periphery engaged between the top of the body 1 and the cap 1^b, and its peripheral lug 2^a (for connecting it with the conductor 3 leading from the line wire) disposed in the offset recess 1^d of the cap; the cap being locked to the body on the plate by a bayonet joint comprising the body lugs 1^e which engage in the angular cap ways 1^f and sealed by the cement 1^g.

A resistor 4, of non-inductive character, has its upper end engaged by the clips 2'' of the conductor 2 and its lower end engaged with a conducting cap or cap plate 5 by its clips 5'. The resistor is thus, by the cap plates 2 and 5, held centrally in the upper part of the compartment 1^h of the case, which is adapted for holding a fluid, particularly air, to be heated, expanded and utilized for creating the blast.

Similar conducting plates, dished to provide the flat bodies 6 combined with oppositely inclined conical parts 6^a and 6^b forming concentric annular edges 6', are separated by the insulators 7 having their ends in engagement with the flat bodies and acting to hold them in the desired relation, with the annular edges 6' separated to provide air gaps, the plates being held in alignment by the ribs 1ⁱ of the body 1. A base 6 is held in engagement with the plate 5 and the several plates are held together and to the insulators 7 by a coiled spring 8 which bears against the base of the lower plate and the inwardly projecting radial fins 1^j of an insulating step 1^k which is seated in the hollow bottom or bottom plug 1^c, the part 1^l containing the central conical hole 1^k. A stem 9, of conducting material, is fixed to the body 6 of the lower plate and passes through the spring and the member 1^l, being held in the desired central position by engagement with the bearings 1^m.

A metal tube 10 extends through the plug 1^c, concentrically with the terminal member 9, and is so spaced therefrom as to form an annular air gap between the terminals 9 and 10. The tube is provided with an annular flange or plate 10^a which is fixed between the bottom of the recess in the plug and the bottom of the member 1ⁱ, the parts 1^c and 1ⁱ being fixed together by cement 1^m.
10 The ground conductor 11 is held in an aperture 1ⁿ in the plug 1^c in engagement with the plate 10^a.

The plug 1^c is locked in place by a bayonet joint comprising the lugs 1^p thereon which 15 enter the angular ways 1^q of the body 1 and the parts are sealed by cement 1^r.

When the line is overcharged, a discharge 20 to ground takes place through the parts 3, 2, 4, 5, 6, 9, 10 and 11, the heat generated by the passage of the discharge through the 25 resistor 4 and across the gaps between the terminals 6' heating and expanding the fluid in the compartment 1^g, the fluid discharging under the pressure in a blast around the cylindrical terminal 9 through the tubular 30 terminal 10, destroying the arc across the gap and sweeping away the ionized air forming a path for the flow of normal current following the discharge.

30 It being known that a given air gap distance will resist a certain voltage or electrical pressure without breaking down or arcing over, the space and number of the air gaps are made such that their summation 35 equals a total air gap space which would not break down under normal voltage but will break down under excessive voltages, liable to injure the apparatus.

When a discharge takes place as a result 40 of excessive voltage, and normal current follows the discharge by reason of the ionization of air, the flow of current is interrupted, if small, at the first half cycle of the gen-

erator wave, or where the flow reverses in direction and passes through zero value. 45 But otherwise the heat, developed by the current passing through the resistor and the arcs across the air gaps, expands the surrounding air confined within the case so that its only escape is through a contracted 50 passage, which increases the velocity of its escape and applies the force of the blast most effectively for obtaining the result desired.

The mechanism described permits the use 55 of comparatively low resistance, just high enough to limit the flow of dynamic current following the lightning discharge to ground without producing serious voltage disturbances on the circuit, or causing lamps connected therewith to flicker or wink, or tripping out circuit breakers or fuses in generator stations, or decreasing the efficiency of protection from lightning.

Having described my invention, I claim: 65

1. A lightning arrester comprising a casing containing a chamber having a restricted outlet, conductors having an air gap between them in said outlet, and insulated conducting plates in said chamber, one of said conductors being supported by one of said plates and said plates having separated edges forming one or more air gaps.

2. In apparatus of the character described, 75 a casing containing a chamber having a restricted outlet, in combination with means comprising conductors having between them an air gap in the path of a blast through said outlet, a plurality of conducting plates in said chamber having air gaps between 80 them, and resilient means for holding said plates in position.

In testimony whereof I have hereunto set my name this 20th day of October, 1916.

JOHN ROBERT McFARLIN.
